WASHING MACHINE WITH WATER
BALANCER

Archibald H. Davis, Sandusky, and Ralph L. Archbold, Euclid, Ohio, assignors to The Apex Electrical Manufacturing Co., Cleveland, Ohio, a corporation of Ohio

Application January 28, 1947, Serial No. 724,876

12 Claims. (Cl. 74—573)

1

This invention relates to washing machines of a centrifugal drying type, and more particularly to means to balance the rotating tub or container of the machine. In washing machines of the type to which this invention relates, the tub or container is provided with a plurality of pockets for the reception of water and the device is arranged so that water is distributed to pockets in order to correct unbalance due to disarrangement of the articles within the tub. When the tub is rotated below its critical speed with unbalance present, the tub and its supports tend to tilt or lean in the direction of the heavy side of the tub. In the type of machine to which this invention relates, this results in a release of water under pressure that is directed to an area of the tub that is substantially 180° displaced from the heavy or unbalanced side of the tub. One form of valve which will accomplish this is shown in the application of Gerald I. Cockerill and Ralph L. Archbold, Serial No. 704,482, filed October 19, 1946, now Patent No. 2,574,170. Since, in the present invention, the water for balancing is emitted from a valve that does not turn with the tub, we have found that there is a time lag or dead space in such construction generally caused by the fact that it takes a certain length of time for water that leaves the valve to traverse the clearance space between the valve and the means on the tub designed to receive the water for balancing purposes. Likewise, it may be that a deflector for the water is required in order to change the direction of flow after leaving the distributing valve, in which case it does not matter how small the clearance is between the rotating tub parts and the fixed valve there would be an appreciable time lag caused by the deflector.

We have found that as a result of this time lag, water that is emitted by the valve opposite the heavy side of the tub does not enter the receiving means on the tub opposite its heavy side, rather it tends to enter the receiving means on the tub at an area which is displaced from the correct point of application in a direction contrary to that of tub rotation.

In addition to the considerations just mentioned, we have found that there are additional factors which must be accounted for if one of the elements of the water balancing relief valve is made of rubber or other resilient material. For one thing, the rotating pressure of the unbalanced member against the rubber valve, such as that described in the Cockerill and Archbold application referred to previously, tends to crowd the rubber of the valve around in the direction of

2

tub rotation. This, in turn, slightly advances the rubber on the opposite or light side of the tub so that the water bleeding orifice tends to lead slightly the area at which it would otherwise occur. On the other hand, there is another phenomenon resulting from use of a rubber valve in that due to hysteresis effects when the rubber is compressed on one side and pressure is relieved thereon on the other side, there is a time lag in the development of the water bleed opening, which lag is in the opposite direction from the rubber crowding effect described previously. Generally speaking, the time lag due to physical separation of the parts which must be traversed by the water stream is greater than the net lag due to the nature of the rubber valve material just described, but it is desirable to consider all of these factors in designing the given machine.

Accordingly, it is an object of this invention to compensate for the effect of the time lags just described and insure that under average conditions the water is directed toward and reaches an area in the tub opposite the area of unbalance, with the tub rotating below its critical speed. We accomplish this by providing channels that direct the water received from the distributing valve into the balancing pockets of the tub, which channels are carried by the tub and are so formed that their terminal ends are displaced from their entrances in the direction of spin. Thereby, under average conditions, time lag is compensated for and the water is distributed to those balancing pockets that are directly opposite the unbalanced areas.

In accordance with the principles of mechanics, there is a reversal of operation of an unbalanced rotating mass when the velocity passes from below the critical speed to above the critical speed of the system. The condition which exists when the mass is rotated below its critical speed has been mentioned. However, when the system is rotated above its critical speed its action is entirely different. Formerly, it was assumed that the washer was being rotated below its critical speed in which case the tub support leans towards the heavy or unbalanced side with the center of rotation of the tub itself revolving conically about a neutral axis. After the tub passes through its critical speed these conditions are reversed and the axis of rotation of the tub moves so that the center of mass lies along the neutral axis of the assembly. This means that insofar as inclination of the supporting shaft of the tub is concerned the situation is diametrically reversed from that existing below the critical speed of the assembly, and water

will emit from the other side of the balancing valve. Therefore, if it is desired to operate a machine above the critical speed, an arrangement of the channels that direct water to the balancing pockets will be somewhat different. For example, if the advance provided by the channel is equal to an angle A in the direction of spin when the system is operated below the critical speed, then it will be necessary to make the angle formed between the outlet of the channel and its inlet equal to 180° minus A against the direction of spin. We therefore contemplate that our novel arrangement of water balancing channels and tub pockets can be designed to serve either type of machine.

We have also found that when a stream of water is emitted from a fixed device such as the distributing valve of the described balancing system, that the trailing wall of the channel strikes the stream of water in a direction perpendicular to its direction of motion causing splattering of the water. Some of the splattered water eventually finds its way into the channel, but it is an even chance that the splattered water will rebound in a direction such that it fails to enter the channel. This reduces the effectiveness of the device and another object of our invention is to insure that all the splattered water is conducted to the balancing pockets. We accomplish this by giving a novel shape to the walls of the water-conducting channels.

We have found that in water balancing machines of the type to which this invention relates, the water balancing pockets distributed about the tub or clothes container tend to gradually become filled as the distribution of the articles in the container changes. Thus, it is not uncommon for the majority or all the pockets to receive balancing water at one time or another during the centrifugal drying operation, and if that operation were continued for an appreciable period of time all the balancing pockets would eventually be filled with water. If this were to occur, no further balancing could be effected and if the articles again shifted within the container, since the water balancing pockets were filled, no further compensating could be had. It is a further object of our invention to make it possible to continue the centrifugal operation for an indefinite period of time without danger of the water balancing pockets becoming filled. This we accomplish by providing each pocket with one or more drain apertures located in the proper position so that the water may drain from each pocket during the extraction operation. These and other objects of our invention will be apparent to those skilled in the art as the following detailed description proceeds.

In the drawings:

Fig. 1 is a cross-sectional view of the washing machine showing the general association of the parts thereof that apply to the present invention;

Fig. 2 is a transverse section through the tub on line 2—2 of Fig. 4, in plan, showing the configuration of the balancing pockets and with parts broken away to show the configuration of the channels to direct water to the balancing pockets;

Fig. 3 is a transverse section through the tub and its mounting taken on line 3—3 of Fig. 2; and

Fig. 4 is a transverse section through the tub taken on line 4—4 of Fig. 2.

The over-all structure of the parts of the washing machine critical to the invention is shown in Fig. 1. The working parts are in a

housing H supported by a plurality of legs 1. The vertical pedestal member D is carried by the legs and supports the majority of elements of the machine. Tub T is supported by the pedestal and may be given the washing action and the spinning action to be hereinafter described. The tub T is mounted in a water-tight container 2 and water may be pumped into the tub through the connection 3 by any convenient pump means. A detailed description of the water circulating means and several other features of control which may be employed, will be found in the co-pending application of James B. Kirby, Serial No. 619,849, filed October 2, 1945.

Motor M drives a conventional V-belt or any convenient driving means to rotate the pulley 5. We may have a speed reduction in the V-belt drive of approximately three to one when using the standard 1750 R. P. M. motor in which case the pulley 5 will turn about 600 R. P. M. which is below the critical speed of the tub. Pulley 5 drives a vertical hollow shaft 6 the lower end of which is supported in the pedestal by bearing 5a and the upper end of which is connected to an upper driving fitting 7. Fitting 7 mounts a bearing 40 to support an upper fitting 8. Fitting 8 carries a member 9, preferably an aluminum casting, that forms the central part of the tub. With this construction, the vertical shaft 10 may spin the tub for drying through the universal joint U. The lower portion of shaft 10 is connected to a brake drum 11 which drum also supports centrifugal clutch shoes 12. During the washing cycle water pressure is not supplied to the operating member B of the brake and spring means 15 or the natural resiliency of the brake band, or both, cause the brake band 13 to grip the drum 11 thereby preventing rotation of shaft 10 and hence of the tub T. Rotation of the pulley 5 and hollow shaft 6, however, is permitted which gives the tub its washing motion.

A source of water under pressure may connect to a remotely controlled solenoid operated valve 21. When valve 21 is opened, water enters line 22 and releases the brake operator B against the spring pressure. Simultaneously, another line 23 conducts water under pressure to the balancing valve V. The controlling means is so arranged that the valve 21 is opened when the machine control is set for drying so that the brake is released to permit the tub to turn and so that the water is available for balancing.

A more detailed view of the tub supporting structure appears in Fig. 3. The fitting 7 that is connected to and rotated by the hollow sleeve 6 supports upper ball bearing 40 described previously, there being a retaining washer 41 for the bearing. The upper fitting 8 has an extension 42 and is clamped to the tub casting 9 by means of a nut 43. A pin 44 provides a driving connection between fitting 8 and tub casting 9. The universal joint U has one yoke connected with the tub driving shaft 10 and the other with the upper fitting 8 so that the shaft 10 is always coupled to the tub.

As indicated in Fig. 1, during the washing, when water pressure to brake operator B is cut off, brake band 13 clamps and holds shaft 10, and by means of universal joint U, the tub is held from rotation. However, it will be noticed that the axis of rotation of the ball bearing 40 and hence that of the tub itself is inclined to the vertical axis defined by shafts 6 and 10. Thus, during the washing cycle, fitting 7 is rotated by sleeve 6, shaft 10 and hence the tub are restrained

from rotation. The tilted bearing 40 causes the geometric axis of the tub to sweep over a conical path having its apex in the universal joint. The universal joint permits this action to take place even though the tub is held from rotation. The result is that any given point in the tub has a rapid rising or falling action and different parts of the mass of water and articles in the tub T are reciprocated in a vertical direction with progressively different phases about the center.

To initiate the drying action, valve 21 is opened to connect water pressure from line 20 to lines 22 and 23. Now brake B releases shaft 10 for rotation and water under pressure is applied to the balancing valve V. During the initial portion of the drying cycle, the reaction of tub T against the wobble action caused by rotation of fitting 7 by sleeve 6, causes the tub to gradually assume the speed of the rotating sleeve 6. At a predetermined velocity of tub rotation, the centrifugal clutch member 12 carried by the brake drum 11 flies out to engage a clutch drum 12a mounted on the rotating pulley 5. Now shaft 10 is locked to hollow shaft 6 so that tub spins at the speed imparted to pulley 5. The structural details of the clutch structure are more fully described in the aforesaid pending application of James M. Kirby.

The tub T has formed around its circumference a series of balancing pockets P and with each pocket there is an associated channel C for directing water released by the balancing valve V into the pockets. Fastening means 30 retain the sheet metal structure of the tub to the central supporting casting 9 and a plate 31 closes the lower ends of the channel C which plate may be fastened to the member 9 by means of screws 32. Apertures 33 may be provided in the tub in between the pockets in order to permit water to escape from the tub during the drying operation.

With the tub spinning below the critical speed, if any unbalance is present, the tub supporting sleeve 6 tends to lean over in the general direction of the heavy side of the tub. This brings balancing valve V into operation, the principal details of which are seen in Fig. 3. A more detailed description of the valve can be found in the co-pending application of Gerald I. Cockerill and Ralph L. Archbold, mentioned previously. The pedestal D supports a metal sleeve member 50 to which is bonded a rubber valve sleeve 51. The other element of the valve comprises an inner relatively non-resilient or metallic member 52 to which is fastened an upper water deflecting disc 53. An upper portion of the rubber member may be formed with one or more ribs that engage and seal against a smooth tapered portion formed on the inner valve member 52. The valve parts are arranged to provide an annular pocket 59 which connects to line 23 so that water under pressure may be introduced for balancing. If there is any unbalance in the tub as it spins, the tub supporting sleeve 6 will tend to lean in the direction of the heavy area. This will tend to open up a small crack or orifice between the rubber member 51 and the tapered portion of metal member 52 at an area generally placed 180° from the unbalanced area. Water under pressure can therefore escape between the parts of the light or high side of the assembly whereupon it is deflected by the disc 53 to find its way into one or more of the channels C formed on the tub. This water is thereby directed into the water balancing pockets P at the periphery of the tub.

It can be seen clearly in Fig. 2 that the outlet

mouth 35 of each channel is displaced from the inlet mouth 38 in the direction of spin. With this structure, water which leaves the deflector plate 53 enters the channel which happens to be 5 radially opposite the axis of water flow, but due to the time lags previously mentioned, the unbalanced area leads the water stream. However, the entrance to this channel is not in alignment with the area of unbalance, but is displaced rearwardly therefrom so that once the water enters 10 the channel, it is directed ahead in the direction of spin toward the area opposite the area of unbalance.

By way of illustrating an application of our 15 invention, we find that when the average size domestic washer tub rotates at approximately 600 R. P. M., with ordinary city water pressures available and with reasonably sized deflector plates, a lead angle of about 45° operates satisfactorily under a range of normal conditions. However, these figures are merely given as examples of a successful construction and it is not intended that these examples be considered as limiting the claims.

Mention has been made of the reversal of conditions when the tub is operated above the critical speed. In this case the supporting shaft members flex in a direction tending to cause the axis of rotation of the entire assembly to coincide with its center of mass. This will result in the shaft and the tub leaning in the opposite direction, due to an unbalance, than that previously described. Therefore, the water emitted from the balancing valve is 180° out of phase 30 from the previously described situation. Nevertheless, it is still desired to direct water to a point displaced 180° from the unbalanced load which means in the example described that the water directing channels should be formed so that their 35 exit is displaced about 135° from their entrance in a direction opposite to the direction of spin.

It will be noted that the water stream leaves the distributing valve and the deflector plate in a form of a radially directed stream. If the walls of the rapidly moving channel adjacent the point of entry of the water were also radial, there would be a splattering of water generally perpendicular to the main stream axis. However, due to irregularities and numerous similar features, 45 the splattered water will tend to deviate from the perpendicular, which means that a certain amount of water will be directed out of the channel. It will be noted that in our construction, entrance parts 37 of the channel wall are curved in the direction of the spin, and we have found that with this structure, most of the splattered water is directed toward the channel to eventually find its way into the associated balancing pocket. We prefer to form the walls 36 of the 50 channel in a spiral configuration so that centrifugal force causes the water to work its way smoothly to the associated balancing pockets.

As the centrifugal action continues and as the 55 articles within the container shift their positions, the point of unbalance continuously changes so that various pockets receive balancing water. If the centrifugal action is continued for an appreciable length of time, it is probable that the pockets will eventually be completely filled, whereupon no further balancing action will be obtained. To prevent this condition, we provide drain apertures 34, and we find that one of such 60 apertures in each pocket prevents the pockets from filling but permits enough water to remain in the pockets to achieve normal balancing action.

Of course, the higher up the wall the drain 34 is positioned, the larger will be the quantity of water in the pockets before the drain functions. Likewise, the larger the aperture, the greater the drain action. Apertures 34 are disposed in the zone normally occupied by a belt of water flung against the outer wall of the balancing pockets during extraction and so they continuously tend to drain the pockets. Although we have illustrated a tub which contains eight balancing pockets and eight channels directing water, the number of pockets and the number of channels may be varied without departing from the essence of the invention. Likewise, we contemplate that there may be more channels than pockets or vice versa. Although our novel balancing structure is particularly useful with the wobble plate, centrifugal type of washer illustrated, we contemplate that the channel arrangement and balancing pocket arrangement of this invention could be used on any container which employs centrifugal drying.

Although we have described the invention in connection with a washing machine wherein water is used as the balancing medium, it is contemplated that the arrangement is equally adaptable to a machine for dry cleaning articles by the use of a suitable liquid solvent such as carbon tetrachloride or the like, and in this instance, the solvent would also be employed as the balancing liquid. Also, the rubber would be replaced by a resilient compound, preferably synthetic, which would be unaffected by the particular liquid solvent employed.

These and other modifications may be made without departing from the spirit of the invention as defined in the appended claims.

What is claimed is:

1. In a washing machine, frame means, a tub, means to support and spin said tub in said frame means for drying, said support means providing for motion of said tub relative to said frame means in response to tub unbalance while spinning, valve means responsive to tub unbalance to emit a stream of water when tub unbalance is present, said valve means being supported so that there is relative rotation between the valve means and the tub, water balancing means including a plurality of channel means carried by said tub to receive said emitted water, each channel means terminating in a pocket offset from its inlet about the axis of rotation, the offset being of a magnitude and in a direction relative to tub rotation so as to compensate for the time lag between initiation of valve action and entry of water into said channel means, and means for supplying water under pressure to said valve means.

2. In a washing machine, frame means, a tub, means to support and spin said tub in said frame means for drying, valve means responsive to tub unbalance to emit a stream of water when tub unbalance is present, said valve means being supported so that there is relative rotation therebetween and the tub when the latter is spinning, water balancing means including a plurality of channel means carried by said tub having inlets spaced from said valve means to receive said emitted water, each channel means terminating in a pocket offset from its inlet about the axis of rotation, the offset being of a magnitude and in a direction relative to tub rotation so as to compensate for the time lag between initiation of valve action and entry of water into said channel means, orifice means in said pockets for drain-

ing fluid during extraction, and means for supplying water under pressure to said valve means.

3. In a washing machine, frame means, a tub, means to support and spin said tub in said frame means for drying, said support means providing for motion of said tub relative to said frame means in response to tub unbalance while spinning, water balancing valve means on said frame means comprising a rubber sleeve, a source of water under pressure for said valve means, said valve means being responsive to tub unbalance to emit a stream of water generally directed toward one side of the tub when tub unbalance is present, said valve means being supported so that there is relative rotation therebetween and the tub, water balancing means including a plurality of channel means carried by said tub to receive said emitted water, the outlet of each channel means being offset from its inlet about the axis of rotation, the offset being of a magnitude and in a direction relative to tub rotation so as to compensate for the time lag between initiation of valve action and entry of water into said channel means.

4. Liquid extraction apparatus comprising a frame, a tub, an assembly comprising means mounting said tub in the frame for limited gyroscopic movement and means to spin the tub, support means non-rotatably mounted in said frame, valve means disposed between said support means and portions of said assembly and arranged so that gyration of said tub opens said valve means, a conduit for conducting a source of liquid under pressure to the inlet of said valve means, water balancing means carried by said tub including a plurality of channels each having an inlet spaced from the outlet of said valve means, each channel terminating in pocket means disposed radially outwardly of and circumferentially offset from the inlet, the offset being of a magnitude and in a direction relative to tub rotation so as to compensate for the time required for liquid to traverse the gap between the outlet of the valve means and the inlets of the channels.

5. Liquid extraction apparatus comprising a frame, a tub, an assembly comprising means mounting said tub in the frame for limited gyroscopic movement and means to spin the tub, support means non-rotatably mounted in said frame, valve means of rubber-like material disposed between said support means and portions of said assembly and arranged so that gyration of said tub compresses and opens said valve means, a conduit for conducting a source of liquid under pressure to the inlet of said valve means, water balancing means carried by said tub including a plurality of channels each having an inlet spaced from the outlet of said valve means, each channel terminating in pocket means disposed radially outwardly of and circumferentially offset from the inlet, the offset being of a magnitude and in a direction relative to tub rotation so as to compensate for the time required for liquid to leave the valve and traverse the gap between the outlet of the valve means and the inlets of the channels.

6. In a washing machine, frame means, a tub, means to support said tub by said frame means to provide for motion of said tub relative to said frame means, means to spin said tub for drying, a plurality of circumferentially arranged water balancing pockets on said tub, a plurality of channels on said tub having radially inner openings to receive said water and side walls to direct water to said balancing pockets, valve means opened by relative motion of said tub and frame means

to direct a stream of water into the openings of one or more of said channels disposed on one side of the tub, the radially inner portions of the channel side walls being raked in a direction opposite to the direction of spin, the radially outer portion of the channel side walls being raked in the direction of spin with the terminus of each channel advanced from its inlet in the direction of tub spin, and means for supplying water under pressure to said valve means.

7. In a washing machine, frame means, a tub, means to support said tub by said frame means to provide for motion of said tub relative to said frame means, means to spin said tub for drying, a plurality of circumferentially arranged water balancing pockets on said tub, a plurality of channels on said tub having radially inner openings to receive said water and side walls to direct water to said balancing pockets, valve means opened by relative motion of said tub and frame means to direct a stream of water into the openings of one or more of said channels disposed on one side of the tub, the radially outer portions of the channel side walls being advanced from the inlet in the direction of spin, a portion of said channel walls adjacent the inlet extending generally radially with the inner ends having a circumferential extent that is opposite to the direction of spin in order to insure that all the water directed toward a channel moves radially outwardly in the channel, and means for supplying water under pressure to said valve means.

8. In a washing machine, frame means, a tub, means to support said tub by said frame means to provide for motion of said tub relative to said frame means, means to spin said tub for drying, a plurality of circumferentially arranged water balancing pockets on said tub, a plurality of channels on said tub having radially inner openings to receive said water and side walls to direct water to said balancing pockets, valve means opened by relative motion of said tub and frame means to direct a stream of water into the openings of one or more of said channels disposed on one side of the tub, the radially outer portions of the channel side walls being advanced from the inlet in the direction of spin, the channel walls being spiral with a portion of the channel walls adjacent the inlet extending generally radially and terminating in a portion that extends circumferentially in a direction opposite to the direction of spin in order to insure that all the water directed toward a channel moves radially outwardly in the channel, the outer portion of said channel walls extending generally circumferentially in the direction of spin, and means for supplying water under pressure to said valve means.

9. In a washing machine, frame means, a tub, means to support said tub by said frame means to provide for motion of said tub relative to said frame means, means to spin said tub for drying, a plurality of circumferentially arranged water balancing means on said tub, said balancing means including a plurality of channel means to receive water, valve means opened by relative motion of said tub and frame means to direct a stream of water into one or more of said channels disposed on one side of said tub, the radially outer portion of each channel means being advanced from its inlet portion in the direction of

spin, and means for supplying water under pressure to said valve means.

10. In a washing machine, frame means, a tub, means to support said tub by said frame means to provide for motion of said tub relative to said frame means, means to spin said tub for drying, a plurality of circumferentially arranged water balancing pockets on said tub, a plurality of channel means to direct said water to the associated water balancing pockets, valve means opened by relative motion of said tub and frame means to direct a stream of water into one or more of said channels disposed on one side of said tub, the inlet of said channels being spaced from said valve means, the outlet of each channel means being advanced from its inlet in the direction of spin, and means for supplying water under pressure to said valve means.

11. In a washing machine, frame means, a tub, means to support said tub by said frame means to provide for motion of said tub relative to said frame means, means to spin said tub for drying, a plurality of circumferentially arranged water balancing means on said tub, said balancing means including a plurality of channel means to receive said water, valve means opened by relative motion of said tub and frame means to direct a stream of water into one or more of said channels disposed on one side of said tub, orifice discharge means for each of said balancing means in the radially outer wall of said pockets to gradually drain said balancing means, said orifice discharge means being disposed in a zone normally occupied by water during drying, and means for supplying water under pressure to said valve means.

12. In a washing machine, frame means, a tub, means to support said tub by said frame means to provide for motion of said tub relative to said frame means, means to spin said tub for drying, a plurality of circumferentially arranged water balancing pockets on said tub, a plurality of channel means to direct said water to the associated water balancing pockets, valve means opened by relative motion of said tub and frame means to direct a stream of water into one or more of said channels disposed on one side of said tub, the outlet of each channel means being advanced from its inlet in the direction of spin, orifice discharge means in an outer wall of said balancing pockets and disposed in the zone normally occupied by water during extraction, and means for supplying water under pressure to said valve means.
